US00D936275S

(12) **United States Design Patent** (10) **Patent No.:** **US D936,275 S**
(45) **Date of Patent:** **** Nov. 16, 2021**

(54) **LIGHT FIXTURE**

(71) Applicant: **HGCI, Inc.**, Las Vegas, NV (US)
(72) Inventor: **Christopher Reynolds**, Vancouver, WA (US)
(73) Assignee: **HGCI, Inc.**, Las Vegas, NV (US)
(**) Term: **15 Years**
(21) Appl. No.: **29/698,163**
(22) Filed: **Jul. 15, 2019**

Related U.S. Application Data

(63) Continuation of application No. 29/600,316, filed on Apr. 11, 2017, now Pat. No. Des. 854,235, which is a continuation of application No. 29/542,729, filed on Oct. 16, 2015, now Pat. No. Des. 788,361.

(57) **CLAIM**

The ornamental design for a light fixture, as shown and described.

DESCRIPTION

FIG. 1 is a perspective view of a light fixture, as viewed from below, showing my new design;

FIG. 2 is a perspective view of the light fixture shown in FIG. 1, as viewed from above;

FIG. 3 is a left side view of the light fixture shown in FIG. 1;

FIG. 4 is a right side view of the light fixture shown in FIG. 1;

FIG. 5 is a front elevation view of the light fixture shown in FIG. 1;

FIG. 6 is a rear elevation view of the light fixture shown in FIG. 1;

FIG. 7 is a top plan view of the light fixture shown in FIG. 1; and,

FIG. 8 is a bottom plan view of the light fixture shown in FIG. 1.

The broken-line disclosure shown in the views is understood to represent portions of the article in which the claimed design is embodied, but which form no part of the claimed design.

1 Claim, 4 Drawing Sheets
